REFRIGERATION

Curtis C. Coons, North Canton, and Stanley R. Cummings, Canton, Ohio, assignors to The Hoover Company, North Canton, Ohio, a corporation of Ohio

Application April 24, 1939, Serial No. 269,676

16 Claims. (Cl. 62—119.5)

This invention relates to the art of refrigeration and more particularly to a novel absorption refrigerating system which is characterized in that it possesses great flexibility, economy and efficiency of operation.

Previously the designs of refrigerating systems of the type in which an inert gas is utilized have been seriously hampered by limitations, inherent in such systems, upon the relative sizes and locations of various portions of the absorption solution circuit. In previous designs it has been necessary to make a rather unsatisfactory compromise between the space limitations imposed by acceptable sizes of domestic refrigerating cabinets, the inherent limits of the system on the height through which the system pressure differentials will serve to elevate the absorption solution and upon the inherent limitations and functionally correct sizes of various portions of the apparatus. Heretofore it has been necessary either to provide an insufficient elevation between different portions of the absorber and to place the absorber in a cramped position in the cabinet or to construct the boiler-analyzer system of an excessive size and particularly of an excessive height in order to provide adequate circulation of the absorption solution. Moreover these functionally unsatisfactory design expedients have resulted in the provision of very large cumbersome boiler-analyzer systems which extend to a height totally unnecessary for efficient operation and which, moreover, require an unnecessarily large charge of the solution to be contained therein, a charge which is unjustified from the viewpoint of functional efficiency. These departures from functionally correct design have brought in their train difficulties due to great pressure differentials between various portions of the apparatus, and to excessive variations in the liquid levels which produce consequent excessive variations in the rate of solution circulation which in turn seriously affects the absorbing and evaporating efficiency of the system as a whole.

Accordingly, it is a principal object of the present invention to provide an absorption refrigerating system which is functionally correct and which will achieve desirable high lifting heights within the apparatus without creating excessive pressure differentials therein, requiring excessive size of various portions of the apparatus and without necessitating that the charge be larger than that indicated for optimum functional efficiency.

It is one object of the present invention to provide an absorption refrigerating system of the inert gas type in which the absorption solution is elevated from the boiler in the absorber in a plurality of easy stages, all of which are operated by a pressure differential within the system which is inadequate to elevate the solution through the desired height in a single step.

It is still another object of the invention to provide an absorption refrigerating system of the inert gas type in which the rate of absorption solution circulation is substantially unaffected by minor system disturbances, such as fluctuations in the liquid level and variations in pressure differential whereby to provide a very constant reliable rate of circulation of the absorption solution.

It is a still further object of the present invention to provide an absorption refrigerating system of the type utilizing an inert gas in which the inherent flexibility of the system permits the same to be incorporated in a domestic refrigerating cabinet with a maximum of space economy and to permit the mechanism containing portions of the apparatus to be decreased in size as compared with previous constructions.

It is a further object of the present invention to provide an absorption refrigerating system of the type utilizing an inert gas in which the absorber may be positioned vertically in a rear air-cooling flue of the apparatus without interfering with the functional design of other portions of the apparatus and without imposing a burdensome circulating load on other portions of the apparatus and without requiring that excessive pressure differentials be maintained in different portions of the system.

Other objects and advantages of the invention will become apparent as the description proceeds when taken in connection with the accompanying drawings in which:

Figure 1 is a diagrammatic representation of an absorption refrigerating system embodying the present invention, and

Figure 2 is a partial side elevational sectional view illustrating the arrangement of the parts illustrated in Figure 1 within a cabinet.

Referring now to the drawings in detail and particularly to Figure 1 thereof, there is disclosed a three-fluid absorption refrigerating system comprising a boiler B, an analyzer D, an air-cooled rectifier R, a tubular air-cooled condenser C, an evaporator E, a gas heat exchanger G, a tubular air-cooled absorber A, a solution reservoir S, a liquid heat exchanger L, and a circu-

lating fan F which is driven by an electrical motor M. These elements are suitably interconnected by various conduits to form a plurality of gas and liquid circuits constituting a complete refrigerating system to which reference will be made in more detail hereinafter.

The above described apparatus will be charged with a suitable refrigerant, such as ammonia, an absorbent therefor, such as water, and a pressure equalizing gas which is inert with respect to the refrigerant and the absorbent, preferably a dense inert gas like nitrogen.

The boiler B may be heated in any suitable manner as by a combustible fuel burner or an electrical cartridge heater.

The application of heat to the boiler B generates refrigerant vapor from the solution normally therein contained. The vapors so generated pass upwardly through the analyzer D in counterflow to strong solution flowing downwardly therethrough. Further refrigerant vapor is generated in the analyzer by the heat of condensation of absorption solution vapor produced in the boiler. The refrigerant vapor is conducted from the upper portion of the analyzer D to the upper portion of the condenser C by means of a conduit 11 which includes the rectifier R.

The lean solution produced in the boiler is conveyed therefrom into the solution reservoir S by means of a conduit 15, the liquid heat exchanger L, and a finned air-cooled conduit 16 which also serves as a solution pre-cooler. As shown, the absorber A comprises two groups of parallel downwardly inclined tubes 18 and 19 which are positioned in staggered relationship in parallel vertical planes and are serially connected together. The arrangement is such that the lower end of any particular one of the conduits in the groups 18 and 19 is connected to the upper end of the next lowest conduit in the other group, thereby to provide a continuous path of flow for the absorption solution and the inert gas. Each individual conduit is individually finned to provide for air-cooling, though a continuous fin may be applied to each group of tubes 18 and 19 if desired. The absorber may be formed from a continuous tube bent into the required shape or from a plurality of preformed tube sections suitably secured together as by welding. It is apparent that the upper end of the vertical absorber is at an elevation very appreciably above the elevation of the solution reservoir S and that the lower end of the absorber is at an elevation slightly above the upper portion of the analyzer D.

It has been proposed previously to elevate the absorption solution from the solution reservoir into the upper end of the absorber by providing a gas lift pump therebetween. This construction operates very satisfactorily in many types of systems; however, there is a definite limit to the height through which the liquid can be elevated by these means both from the viewpoint of the available pressure differential in the inert gas circuit for operating the pump and also because the sensitivity of the circulating mechanism to minor system disturbances, such as minor variations in pressure differentials and variations in liquid levels which tend to limit the practical height through which the solution may be elevated by the gas lift pump. Furthermore, considerations of the size of the circulating fan, the cost of the apparatus, the design of the gas heat exchanger, evaporator and absorber all tend to

fix a fairly rigid value for the gas pressure differential which should be developed across the circulating fan, all of which in turn impose rather rigid limitations upon the design and arrangement of the absorber and of the other parts of the solution circuit.

In accordance with the present invention, however, the lean solution which is supplied to the reservoir S is conveyed therefrom by means of a conduit 21 into the bight portion of a U-shaped twin gas lift pump 22 which discharges into a collection and separation vessel 23. Pumping gas is supplied to each of the legs of the pump 22 through an inverted U-shaped conduit 25 which connects to the legs of the pump 22 below the liquid level normally prevailing therein. Pumping gas is supplied to the bight portion of the inverted conduit 25 by means of a conduit 27 which connects to the discharge conduit 28 of the circulating fan F. By this construction the lean solution is elevated into the vessel 23 alternately through the legs of the pump 22 by gas lift action. The pump per se is disclosed and claimed in the co-pending application of Curtis C. Coons and Rudolph S. Nelson, Serial No. 169,988, filed October 20, 1937, Patent No. 2,240,176.

A twin gas lift pump is one having one or more elevating conduits which are in unobstructed communication with a source of gas under pressure at a level below the liquid level prevailing in the elevating conduit under static conditions, are in open and unobstructed communication with a source of the liquid to be pumped, and are in unobstructed communication with a conduit or chamber adapted to house an oscillating piston or body of liquid. As is illustrated in this application, the lowest of the two twin-gas lift pumps shown in Figure 1 comprises an upstanding U-shaped conduit which includes a pair of elevating conduits—the legs of the U—designated by the reference character 22 and an inverted U-shaped conduit 25 which communicates with a source of gas under pressure and with each of the elevating conduits 22. Communication with a source of liquid to be pumped is provided by the conduit 21 opening into the bight portion of the U-shaped pump structure. The oscillating column or chamber is the bight portion of the U-shaped conduit.

The lean solution which collects in the bottom portion of the vessel 23 is conveyed therefrom by means of a conduit 30 into the bight portion of a second U-shaped-twin gas lift pump 31 which discharges into a second collection and separation vessel 32. Pumping gas is supplied to the twin pump 31 by means of an inverted U-shaped conduit 34 which connects with the legs of the pump 31 below the liquid level normally therein contained.

Gas is supplied to the bight portion of the conduit 34 by means of a conduit 35 which communicates with the conduit 27 previously described.

The lean solution supplied to the vessel 32 is drained therefrom by means of a conduit 38 into the suction conduit 37 of the circulating fan which connects directly to the top portion of the absorber A.

The solution reservoir S, the separation chamber 23 and the separation chamber 32 are all vented to the conduit 37 by means of conduits 38, 39 and 40, respectively, which join a conduit 41 directly connected to the conduit 37. By reason of this venting system each gas lift pump operates with the maximum available pressure differ-

ential found in the system and the pressure differential is substantially constant because the circulating fan F operates at a constant speed.

The gas lift pump 22 has a capacity slightly in excess of the gas lift pump 31 which is designed to elevate the quantity of absorption solution which should be supplied to the absorber. The vessel 23 is provided with a return drain 43 which connects to the lean solution supply conduit 21. The position of the return drain 43 determines the liquid level in the vessel 23 and hence the depth of immersion of the elevating pump 31, and, due to the fact that the capacity of the pump 22 is greater than that of the pump 31, this depth of immersion remains constant independently of any variations which may occur in other parts of the system. Consequently, there will be a recirculation of a small quantity of absorption solution through the gas lift pump 22 and the return conduit 43.

The lean solution which is supplied to the upper portion of the absorber by the conduits 36 and 37 flows downwardly therethrough by gravity counter to an upwardly flowing mixture of inert gas and refrigerant vapor. The refrigerant vapor content of the mixture is absorbed by the solution and the heat of absorption is rejected to cooling air passing across the absorber tubes and the fins mounted thereon.

The strong solution formed in the absorber by the absorption of refrigerant vapor drains into the rich gas inlet conduit 53 at the lower end of the absorber and is conveyed therefrom into the upper portion of the analyzer D by the conduit 44, the inner pass of the liquid heat exchanger L and the conduit 45.

The refrigerant vapor supplied to the condenser C is liquified therein by heat exchange with atmospheric air and is discharged from the bottom portion thereof into the bottom portion of the evaporator E through a conduit 46 which includes a U-shaped liquid seal and pressure balancing column forming portion 47. The conduit 46 is also vented by means of the conduit 48 to the rich gas side of the gas heat exchanger G.

In the bottom portion of the evaporator E the liquid refrigerant contacts lean gas which is conveyed from the top portion of the absorber A by way of the conduit 31, the circulating fan F, the conduit 28, the outer path of the gas heat exchanger G, and a conduit 49. The inert gas sweeps or drags the liquid refrigerant upwardly through the evaporator as the liquid is evaporating thereinto to produce useful refrigeration. As herein illustrated, the evaporator is shown diagrammatically. However, any suitable arrangement and form of evaporator may be utilized. A preferred construction is illustrated and described in the co-pending application of Curtis C. Coons and William H. Kitto, Serial No. 386,395, filed April 2, 1941.

After passing through the lower portion of the evaporator E the inert gas and liquid refrigerant are discharged into the upper enlarged diameter finned box-cooling conduit 50 after which the rich gas produced by the evaporation of the liquid refrigerant is conveyed from the box-cooling conduit 50 into the rich gas side of the gas heat exchanger G by means of a conduit 52. After passing through the gas heat exchanger the rich gas is conveyed therefrom to the bottom portion of the absorber A by means of a conduit 53. The rich gas then passes upwardly through the absorber A in counterflow relationship to the absorption solution flowing

downwardly therethrough in the manner described heretofore.

The evaporator is provided with a safety anti-block drain 56 which is connected between the upper portion of the lowest evaporator conduit and the rich solution return conduit 44.

Referring now to Figure 2, the manner in which the apparatus is enclosed in a refrigerator cabinet will be described. The apparatus includes a cabinet 60 comprising an insulated freezing and storage chamber 61 which overlies a shallow mechanism compartment 62 and is provided with a rear air-cooling flue 63. The evaporator E and the box-cooling conduit 50 are mounted within the chamber 61 and the freezing portion of the evaporator E will be enclosed in a suitable casing 54 for housing freezing trays and the like, as illustrated.

The rear wall of the insulated compartment 61 is provided with an opening 66 which receives an insulated panel 67 of a size to permit the evaporator to pass through the opening 66 and to seal that opening. A suitable gasket 68 is provided to prevent air leakage around the margins of the panel 67.

The gas heat exchanger G is partially embedded in the rear insulated wall of the compartment 61 and in the panel 67.

As is illustrated clearly in Figure 2, the condenser C extends diagonally across the upper portion of the flue 63 and the air-cooled absorber A is vertically mounted in the lower portion thereof with its lower end positioned at an elevation slightly above the elevation of the liquid inlet to the analyzer D. The gas lift pumps 22 and 31 and their associated conduits and separating vessels 23 and 32, respectively, are positioned in the extreme rear portion of the mechanism compartment 62 and beneath the lower end of the flue 63. For purposes of clarity in this figure the gas lift pumps are shown as being of the single lift rather than of the twin lift type, though it should be understood that the twin lift type is to be preferred even though either type may be utilized without departing from the spirit of the present invention.

Cooling air may be admitted to the bottom portion of the flue 63 and the mechanism compartment 62 in any desired manner. As illustrated the lower end of the mechanism compartment, and particularly that portion thereof directly beneath the flue 63, is open to allow cooling air to flow inwardly thereof and upwardly through the flue 63 to remove the heat of absorption, condensation and rectification from the apparatus.

Figure 2 well illustrates the manner in which the present invention allows the mechanism compartment to be made of extremely low height and permits the absorber to extend vertically in the flue without requiring an excessively large fan, without requiring an excessively large boiler-analyzer and without imposing any pumping load on the apparatus approaching or above its maximum capacity for that purpose.

In accordance with the present invention there is therefore provided an absorption refrigerating system in which extreme flexibility is provided, accuracy of absorption solution circulation rate is provided and the position of the absorber relative to the boiler-analyzer may be selected within a wide range of possibilities without imposing any undue loads upon the apparatus requiring excessive sizes or proportions thereof and with-

out requiring the use of abnormally large quantities of absorption solution in the charge.

Though the present invention may be practiced by utilizing single lift pumps in place of twin gas lift pumps 22 and 31 illustrated in Figure 1, the twin lift gas type of pump is to be preferred as it is more efficient and will elevate liquid through a greater height for a given depth of immersion and the gas supply pressure than will a corresponding single lift pump.

While the invention has been illustrated and described herein in considerable detail, it is not to be limited thereto and various changes may be made in the arrangement, construction and proportion of parts without departing from the spirit of the invention or the scope of the appended claims.

We claim:

1. Absorption refrigerating apparatus comprising a solution circuit including a boiler and an absorber, an inert gas circuit including an evaporator and said absorber, said solution circuit including a plurality of serially connected circulating devices positioned at different elevations arranged to convey solution from said boiler to said absorber, one of said circulating devices having a greater capacity than the circulating device to which it supplies solution, and means for returning to the inlet portion of said one circulating device the excess solution flowing therethrough.

2. Absorption refrigerating apparatus comprising a solution circuit including a boiler and an absorber, an inert gas circuit including an evaporator and said absorber, said solution circuit including a plurality of serially connected twin gas lift pumps arranged to convey solution from said boiler to said absorber.

3. Absorption refrigerating apparatus comprising a solution circuit including a boiler and an absorber, an inert gas circuit including an evaporator and said absorber, said solution circuit including a plurality of serially connected gas lift pumps arranged to convey solution from said boiler to said absorber, and means for leading a portion of the gas flowing in said inert gas circuit into said gas lift pumps to operate the same.

4. Absorption refrigerating apparatus comprising a solution circuit including a boiler and an absorber, an inert gas circuit including an evaporator and said absorber, and power driven means for propelling the inert gas through said inert gas circuit, said solution circuit including a plurality of serially connected gas lift pumps arranged to convey solution from said boiler to said absorber.

5. Absorption refrigerating apparatus comprising a solution circuit including a boiler and an absorber, an inert gas circuit including an evaporator and said absorber, a power driven circulator in said inert gas circuit, said absorber comprising a sinuous finned conduit having one end connected to drain solution into said boiler, means for elevating absorption solution from said boiler into said absorber comprising a pair of twin gas lift pumps, one of said pumps being connected to receive absorption solution from said boiler and to discharge the same into a separation chamber which is connected to the inlet portion of the other of said pumps, the other of said pumps being arranged to discharge into said absorber, means for supplying pumping gas from the discharge side of said circulator to said twin gas lift pumps, and means for subjecting

the discharge side of said pumps to the pressure prevailing in the suction side of said circulator.

6. Absorption refrigerating apparatus comprising a solution circuit including a boiler and an absorber, an inert gas circuit including an evaporator and said absorber, said solution circuit including a plurality of serially connected gas lift pumps arranged to convey solution from said boiler to said absorber, reservoirs situated in the supply line of each of said pumps, and means for venting said reservoirs and the discharge sides of said gas lift pumps to the inert gas circuit.

7. Absorption refrigerating apparatus comprising a solution circuit including a boiler and an absorber, an inert gas circuit including an evaporator and said absorber, power driven means for circulating the pressure equalizing medium through said pressure equalizing medium circuit, said absorber being positioned relatively to said boiler at such an elevation that the pressure differential developed by said circulating means is inadequate to elevate solution directly from said boiler to said absorber and means operated by such pressure differential for elevating solution from said boiler into said absorber comprising a plurality of serially connected pressure equalizing medium operated pumps each of which is arranged to elevate the absorption solution through a height within the elevating limits of such pressure differential.

8. Refrigerating apparatus including a cabinet having an insulated refrigerating compartment, a shallow chamber underlying said compartment, an air duct extending upwardly alongside said compartment, an evaporator in said compartment, an upstanding tubular air-cooled absorber in said duct, a boiler in said chamber, a plurality of serially connected gas lift pumps arranged to elevate absorption solution from said boiler into said absorber, said gas lift pumps being positioned at different elevations, the lowest of said gas lift pumps being positioned in said chamber to receive absorption solution by gravity from said boiler and the highest of said gas lift pumps extending upwardly in said duct and arranged to discharge absorption solution into the upper portion of said absorber, a condenser in the upper portion of said duct connected to receive refrigerant vapor from said boiler and to supply refrigerant liquid to said evaporator, and means for conveying refrigerant vapor from said evaporator to said absorber, and means providing for circulation of an inert gas between said evaporator and said absorber and for supplying pumping gas to said gas lift pumps.

9. Refrigerating apparatus including a cabinet having an insulated refrigerating compartment, a shallow chamber underlying said compartment, an absorption refrigerating apparatus of the type utilizing an inert gas associated with said cabinet including a boiler in said chamber, a vertical air-cooled absorber in said duct extending to a level materially above the top wall of said chamber, a pair of serially connected gas lift pumps arranged to elevate absorption solution from said boiler into said absorber, power driven means for propelling inert gas through a circuit including said absorber and means for leading gas from said circuit into said pumps to operate the same.

10. Refrigerating apparatus comprising a cabinet including an insulated storage chamber having an air cooled machinery compartment associated therewith, an absorption refrigerating

machine associated with said cabinet comprising an inert gas circuit including an evaporator positioned in said chamber and an upright tubular air cooled absorber in said compartment, a solution circuit including a generator and said absorber, an air-cooled condenser in said compartment connected to receive refrigerant vapor from said generator and to supply refrigerant liquid to said evaporator, and a plurality of serially connected circulators in said solution circuit connected to elevate solution from said generator into said absorber, said circulators being positioned at different elevations, the lowest of said circulators being positioned to receive absorption solution by gravity from said generator and to lift the solution to a higher elevation, the highest of said circulators being arranged to receive absorption solution elevated from said generator and to lift such absorption solution into the upper part of said upright absorber.

11. Refrigerating apparatus comprising a cabinet including an insulated storage chamber having an air cooled machinery compartment associated therewith, an absorption refrigerating machine associated with said cabinet comprising an inert gas circuit including an evaporator positioned in said chamber and an upright tubular air cooled absorber in said compartment, a power driven circulator in said inert gas circuit, a solution circuit including a generator and said absorber, an air cooled condenser in said compartment connected to receive refrigerant vapor from said generator and to supply refrigerant liquid to said evaporator, said absorber being positioned relatively to said boiler at such an elevation that the pressure differential developed by said circulator is inadequate to elevate solution directly from said generator to said absorber, and a plurality of vertically spaced serially connected gas lift pumps included in said solution circuit for elevating absorption solution into said absorber, each of said pumps being arranged to elevate the absorption solution through a height which is within the elevating limits of such pressure differential.

12. Refrigerating apparatus comprising a cabinet including an insulated storage chamber having an air cooled machinery compartment associated therewith, an absorption refrigerating machine associated with said cabinet comprising an inert gas circuit including an evaporator positioned in said chamber and an upright tubular air cooled absorber in said compartment, a power driven circulator in said inert gas circuit, a solution circuit including a generator and said absorber, an air cooled condenser in said compartment connected to receive refrigerant vapor from said generator and to supply refrigerant liquid to said evaporator, said absorber comprising a sinuous tube bent to form a plurality of alternately oppositely inclined serially connected conduits, the conduits of like inclination lying in a common plane spaced from the conduits of opposite inclination and heat rejecting fins attached to said conduits, said absorber being positioned relatively to said boiler at such an elevation that the pressure differential developed by said circulator is inadequate to elevate solution directly from said generator to said absorber, and a plurality of vertically spaced serially connected gas lift pumps included in said solution circuit for elevating absorption solution into said absorber, each of said pumps being arranged to elevate the absorption solution through a height

which is within the elevating limits of such pressure differential.

13. Refrigerating apparatus comprising a cabinet including an insulated storage chamber having an air cooled machinery compartment associated therewith, an absorption refrigerating machine associated with said cabinet comprising an inert gas circuit including an evaporator positioned in said chamber and an upright tubular air cooled absorber in said compartment, a power driven circulator in said inert gas circuit, a solution circuit including a generator and said absorber, an air cooled condenser in said compartment connected to receive refrigerant vapor from said generator and to supply refrigerant liquid to said evaporator, said absorber being positioned relatively to said boiler at such an elevation that the pressure differential developed by said circulator is inadequate to elevate solution directly from said generator to said absorber, a plurality of vertically spaced serially connected twin gas lift pumps included in said solution circuit for elevating absorption solution into said absorber, each of said pumps being arranged to elevate the absorption solution through a height which is within the elevating limits of such pressure differential, and means for leading gas from said inert gas circuit into said pumps for operating the same.

14. In combination, a cabinet having a food storage compartment and an apparatus compartment including a vertically positioned air flue, an evaporator in said storage compartment, a vertically positioned absorber in said flue, a closed inert gas circuit between the evaporator and absorber, a solution circuit including said absorber having a solution level below the top of said absorber, a circulator unit in said gas circuit for circulating the gas in its circuit and for raising the pressure therein above that normally prevailing in the evaporator and means for utilizing a portion of the gas at its raised pressure for raising the solution to the top of said absorber.

15. In combination, a cabinet having a food storage compartment and an apparatus compartment including a vertically positioned air flue, an evaporator in said food storage compartment, a condenser and a vertically positioned absorber in said flue, said evaporator being positioned above the bottom of said condenser, a closed inert gas circuit between the evaporator and absorber, a circulator unit in said gas circuit for raising the pressure of the gas and for circulating the gas in its circuit, means for utilizing a portion of said gas at said raised pressure for raising solution to the top of said absorber, and means for leading condensed refrigerant from said condenser to the bottom of said evaporator, said evaporator and said gas circuit being so constructed and arranged that the remainder of said gas at its raised pressure will raise the liquid refrigerant upwardly through the evaporator.

16. In combination, a cabinet having a food storage chamber and an apparatus compartment including a vertically extending air duct, an evaporator arranged to refrigerate said food storage chamber, a vertically extending absorber in said duct, a closed inert gas circuit including said evaporator and said absorber, a solution circuit including said absorber and a generator and having a liquid level below the upper portion of said absorber, a circulator in said gas circuit for circulating the gas through said circuit and for raising the pressure of the inert gas, a condenser in said duct extending to a level below the upper

portion of said evaporator and connected to receive refrigerant vapor from said generator and to supply liquid refrigerant to the lower portion of said evaporator, gas lift pump means arranged to elevate absorption solution from said generator to the upper portion of said absorber, and means for supplying a portion of the inert gas at the raised pressure to said gas lift pump means

to operate the same, said evaporator and said circulator being so constructed and arranged that the gas at the raised pressure flows upwardly through said evaporator with sufficient velocity and pressure to raise liquid refrigerant upwardly through said evaporator.

CURTIS C. COONS.
